(57) **CLAIM**

We claim the ornamental design for a carry loop with storage pouch, as shown and described.

DESCRIPTION

FIG. 1 is a top perspective view of a carry loop with storage pouch in use with a bottle showing our new design;
FIG. 2 is a bottom perspective view of a carry loop with storage pouch;

FIG. 3 is a front elevational view thereof;

FIG. 4 is a rear elevational view thereof;

FIG. 5 is a right side view thereof;

FIG. 6 is a left side view thereof;

FIG. 7 is a top plan view thereof; and,

FIG. 8 is a bottom view thereof.

The broken lines in the drawings depict environmental subject matter only and form no part of the claimed design.

1 Claim, 8 Drawing Sheets
